UNITED STATES PATENT OFFICE

154,544

DESIGN FOR A PHOTOGRAPHIC ENLARGER

Morris Kaplowitz, Brooklyn, N. Y., assignor to
Federal Manufacturing & Engineering Corp.,
a corporation of New York

Application October 30, 1947, Serial No. 142,208

Term of patent 14 years

(Cl. D61—1)

To all whom it may concern:

Be it known that I, Morris Kaplowitz, a citizen of the United States, residing in the city of New York, Borough of Brooklyn, in the county of Kings and State of New York, have invented a new, original, and ornamental Design for a Photographic Enlarger, of which the following is a specification, reference being had to the accompanying drawing, constituting a part thereof.

Fig. 1 is a side perspective view of a photographic enlarger, with the enlarger head in a substantially normal vertical position, showing my new design;

Fig. 2 is a front perspective view of the same, with the enlarger head tilted at an angle from the vertical; and

Fig. 3 is an enlarged fragmentary view of a portion of the design, for the purpose of bringing out more clearly the details thereof.

I claim:

The ornamental design for a photographic enlarger, substantially as shown and described.

MORRIS KAPLOWITZ.
